UNITED STATES PATENT OFFICE.

JASPER A. McCASKELL, OF SALT LAKE CITY, UTAH, ASSIGNOR, BY MESNE ASSIGNMENTS, TO UNITED FILTERS CORPORATION, A CORPORATION OF DELAWARE.

HEAD-LOCKING MECHANISM.

1,244,222.

Specification of Letters Patent. Patented Oct. 23, 1917.

Application filed January 19, 1915. Serial No. 3,143.

To all whom it may concern:

Be it known that I, JASPER A. McCASKELL, a citizen of the United States, residing at Salt Lake City, in the county of Salt Lake and State of Utah, have invented certain new and useful Improvements in Head-Locking Mechanisms, of which the following is a specification.

My invention which relates to certain new and useful improvements in head-closing mechanisms for all kinds of tanks or receptacles, has been found of great value when used in connection with apparatus for separating and filtering solids of whatever nature from liquids, the present invention being an improvement on and shown in connection with the locking mechanisms disclosed in Patents Nos. 1,015,960, dated January 30, 1912, and 1,015,961, dated January 30, 1912, issued to D. J. Kelly.

The present invention consists, essentially of an improved quick-locking mechanism employing an automatic toggle arrangement whereby the motion used in unlocking the connection between the movable head and the tank is also automatically used to positively move said head at any desired distance from the tank, the reverse positive motion moving the head into position against the tank is automatically used to positively lock said head against the tank thereby giving a fluid tight joint between the open end of the tank and the movable head therefor.

In the accompanying drawings forming a part of this specification and in which similar reference characters indicate like parts in the several views;

Figure 1 is a top plan view of a filter press embodying my invention.

Fig. 2 is a side elevation of the same.

Fig. 3 is a detail of a toggle mechanism to be referred to.

Fig. 4 is a top plan view of a filter press showing a head locking mechanism of modified form.

Fig. 5 is a side elevation of Fig. 4.

Fig. 6 is an elevation showing a means for automatically controlling the linear motion of the carriage.

Fig. 7 is an enlarged end view of the same.

In the said former patents are disclosed arrangements for hand and hydraulically locking the head connection between the tank and head or filter carrier. I have

found that both these arrangements are suitable for the purposes for which they were designed, but it has since been found that in certain practice the head locking devices are positive and that the removal of the head and its carrier from the tank or movement of same into position toward the tank is not positive enough. In making this movement positive, through the proper motor actuating device, I have combined the unlocking and traveling motion and traveling and locking motion in such a way that a thoroughly positive and most economical effect is gained, thus enabling one operator to effectively and positively unlock, open, close and lock several pressure tanks at will.

This object is attained by the use of suitable mechanism operated by motor and transmission means combined with toggle and tripping devices which I will hereinafter describe and claim.

Referring to Figs. 1 and 2, the locking head, A', of the pressure tank, A, is, like in previous patents, mentioned, provided with a rigid shaft, 1, which extends outward from its center and axially in line with the tank, said shaft having a screw-threaded outer end. On the shaft, 1, is slidably mounted a sleeve, 2, having ears or lugs, 2', to which are pivotally mounted the inner ends of the radially disposed locking levers, 3, the outer ends of which are curved or cam-shaped and adapted to slidably operate between suitable lugs or ears, 4, projecting from the front face near the periphery of the head, suitable springs, 5, being also preferably employed and against which the outer edges of the levers substantially bear whereby the springs assist in maintaining the levers against the lugs. In the foregoing respects, the levers and their means of attachment do not depart materially from the substantially similar parts found in the aforesaid prior patents.

The sliding sleeve or collar, 2, is formed with other lugs or ears, 6, and to these are pivoted the rear ends of links, 7, the forward ends of which are in turn pivoted to the rear ends of similar links, 8 and 9. The front ends of the links, 8, are pivoted to the movable cross-bar, 10, and the front ends of links, 9, are pivoted to the lugs, 11, of a suitable collar, 12, against the outer face of which bears a nut, 13, which is threaded to the outer end of the shaft, 1, and is designed

to adjust the tension of the head, A', of the tank, for when the nut is rotated, it causes the lever spacing collar, 2, to move forward or backward and in this manner the tension 5 of head, A', against a gasket usually placed in a groove in the ring, 14, of the tank can be regulated at will. The tension-adjusting nut, 13, is constructed and operated substantially as set forth in prior patents 10 mentioned. From the foregoing description it will be apparent that links, 7, 8 and 9, constitute a toggle-lever connection which is actuated by the cross-bar, 10, having an aperture at its center so it can pass 15 over the shaft, 1, and nut, 13, while moving back and forth, said cross-bar being connected on both outer ends to the head, A', by links, 16 and 17 (see Fig. 3) and to the transmission cables, 21, (see Figs. 1 and 2). 20 The forward ends of the links, 16, are pivoted to the lug, 15, and the cross-bar, 10; the rear ends of the links, 16, are pivoted to the front end of a lever, 17, having an inclined arm, 19, and the rear end of the lever, 25 17, is pivoted to the head, A', by means of lugs, 18. As shown in Fig. 1, the described arrangement of lever and links is intended for each end of the cross-bar, 10. Fixed to the tank-supporting beams, 22, is a tripping 30 device, 20, having an inclined or cam-surface, 20', which is so placed as to engage the outer end of the arm, 19, of the lever, 17, whereby the latter in passing over the incline 20', will throw the links, 16 and lever, 35 17, out of the dead center position as indicated by dotted lines in Fig. 3, and full lines in Fig. 2.

The mechanical means shown for actuating the cross-bar, 10, and the resultant 40 link-and-toggle locking means comprise the transmission cables, 21, passing over the motor-propelled drums, 23, at the rear of the tank-carrying beams, 22, and over the sheaves, 24, at the front end of these beams. 45 The cables are fastened to the cross-bar, 10, by means of lugs, 25, and are made adjustable by means of turnbuckles or other adjusting devices, 26. The cross-bar, 10 is supported movably by wheels, 35, running 50 on rails, 31.

The rear transmission drums, 23, are connected by a shaft, 27, which is propelled by any suitable motor mounted in a suitable gear casing, 28. Usually I choose an air 55 or electric motor for this purpose which in its turn is usually equipped with a valve, shift, or switch, so that the motor or driving mechanism can be reversed, by hand or automatically through the head, A', reaching its 60 ultimate desired distance from the open end of the tank, A. The head, A', may be in this instance, connected similarly to the arrangement shown in the patents herein mentioned by means of beams 29 to wheels running 65 on tracks inside of the tank, A, and

the head, A', itself carries a corresponding front set of wheels, 30, running on outer tracks, 31. This arrangement permits the head and its rigid carriage being removed at any desired distance from the tank, A. 70

From the foregoing description, it will be seen that when the head is closed and locked in position against the open end of the tank, A, the levers, 3 and toggles, 7, 8 and 9, and actuating cables, 21, and cross-bar, 10, will appear as in the full-line position of Figs. 1 and 2, but when it is desired to unlock the head and remove the same with the carrier from the tank, as shown in dotted lines in Figs. 1 and 2, the motor is started. 80 At first, the linear cable motion, transmitted from the motor, tends to pull the movable cross-bar, 10, outward from the tank head, A', thus unfolding the links, 8 and 9 (as indicated by dotted position Fig. 1) and pulling the links, 16 and 17, into the straight dead-center position shown in Fig. 3. This unfolding of the links, 8 and 9, results at the same time in pulling the collar, 2, with the lever ends of the locking arms, 3, along the shaft, 1, thereby causing the levers, 3, to slidably fulcrum on the lugs or bearings, 4, and thereby loosen the U-bolts, a, and unlock the head so that the withdrawn ends of levers, 3, will clear the 90 U-bolts, thus permitting the further linear motion of the cables, 21, to pull the head, A', and its carriage from the tank. This will happen as soon as the cross-bar, 10, has reached its ultimate outward travel relative 95 to the head, A', by the links, 16 and 17 being moved into the straight, dead-center position, shown in Fig. 3. Thus the same linear motion that has caused the cross-bar and its series of locking toggles to release 100 the head from the tank continues and removes the head, A', at a desirable distance from the tank, so that the carriage or tank may be completely accessible. When it is again desired to return the carriage and its 105 head to the tank and to lock the same in position, the motor is reversed and the carriage drawn back into the tank by the cables, the locking levers first remaining in the dotted position shown in Figs. 1 and 2 110 and in the full-line position, shown in Fig. 3, because the toggles of links, 16 and 17 being in dead-center do not permit the cross-bar to move nearer the head, A', until the 115 dead-center position is disturbed. This happens automatically as soon as the head, A', is sufficiently near the tank, A, when the arm, 19, of the link, 17, (Fig. 3) comes in contact with the tripping device, 20, whereby the return motion of the carriage forces 120 the end of the arm, 19, up the cam or incline, 20', thus breaking the dead-center position, so that the head first comes in contact with the ring, 14, of the tank, A, and the linear motion of the cables, 21, pulls the 125 130

- cross-bar, 10, nearer the head thus again actuating the toggles of links, 16 and 17, to cause them to assume the position dotted in Fig. 3, and shown in full lines in Figs. 1 5 and 2, and firmly locking the head in place. As soon as the links, 7 and 9, have assumed dead-center position shown in full lines in Fig. 1, the links, 8, are at right-angles to them as dotted in Fig. 1, behind the cross-bar, 10, and the locking is complete and the motor is now cut-out by hand or either automatically cut out by mechanism refusing to move any farther or by any properly adjusted lug on cables, 21, striking or coming 15 in contact with a cut-out.
- It is not essential that the cross-bar actuated toggle-levers, 7, 8 and 9, should be arranged to operate as before described, nor do I limit my invention thereto for said invention is of broader scope than any mere arrangement of parts and it comprehends and includes any mechanism in combination with the head and traveling carrier and operated in conjunction with the carrier and 20 through the motion that tends to move the head and carrier away from or toward the tank, and is designed for automatically unlocking the head, moving same from tank, returning same to tank, and again locking 25 same in position. Accordingly, in Figs. 4 and 5, I show another and more simple form of mechanism for the purposes stated. In this modified construction, the locking levers, 3', and movable collar, 2'', are actuated to move along the projecting shaft through the arrangement substantially as disclosed in Patent No. 1,015,961, before mentioned. The shaft, H', moving the cranks, G G', which in their turn move the 30 toggle links, F F', thus actuating the locking mechanism, is made to partially rotate by passing the cables, 21, around the cable drums, 32, attached to the shaft, H'. In place of the link-mechanism, 16 and 17, in 35 Fig. 3, the escape catch, 33', is attached to a bearing X, and engages a disk, M, fastened rigidly to the shaft, H'. The catch, 33', is pivoted at 34', and it is clear that when the same is released from the notch in the disk, 40 M, the latter is free to turn. It will be seen that upon moving the head and its carrier toward the tank through the cables being actuated by the motor device already described that the shaft, H', cannot turn in its 45 bearing until the escape catch, 33', is released. This automatically takes place when the lower end of the catch, 33', strikes the cam tripping device, 20, already described in the previous arrangement.
- Through this action, the head, A', comes in contact with ring, 14', at the same time the catch, 33', is released through coming in contact with the tripping device, 20. As soon as the motion of the head, A', is arrested by 50 the ring, 14', the linear motion of the cables
- passing around the drums, 32, causes the shaft, H', to rotate thereby actuating levers, G G', links, F, F', and the slidable collar with the locking levers, as hereinbefore specified. As soon as the head is firmly 70 locked in place, the cable motion is arrested by automatically cutting out the motor substantially as before described.
- It may be desirable to automatically move the carrier and its head to and from the 75 tank while the locking levers and adherent mechanism are in an unlocked position without actuating the locking mechanism. In this case the lower cable, 21, can be supplied with a lug or trip that comes in contact with 80 a motor switch, thus reversing the motor at any moment desired and causing the carrier and head to move to and from the tank at will.
- In Figs. 6 and 7 I illustrate an automatic 85 carriage control mechanism which will be found useful in connection with the salient parts of my invention.
- In this instance, the transmission cable, 21, is connected to the cross bar, 10, by means 90 of lugs, 25, said cross bar being attached to the head, A', by links, substantially as heretofore explained. The transmission cable extends from the lug, 25, over the sheave, 24, at the front end of beams, 22, and returns 95 below the track, 31, and extends over the motor propelled drums, 23 and thence extends to a lug, 25', on the cross bar, 10, thus making a complete circuit. At any suitable place on this cable, 21, a lug, 36, is securely 100 fastened, said lug being so constructed that it will engage and pass through suitable stops, 46, at the will of the operator, and which stops are securely fastened to the shaft, 44, at any desired distance apart to 105 thereby regulate the travel of the carriage.
- A hand wheel, 43, fixedly secured to the shaft, 42, is designed to operate a lever, 39, which in turn rotates the shaft, 44, in either direction, said lever, 39, being attached to a 110 boss, 40, which in turn is keyed to the shaft, 42. By pressing down on the shaft, 42, the lever, 39, rotates the shaft, and thus operates the stop, 46.
- In Fig. 7 the operating mechanism is 115 shown by full lines in its neutral position, i. e. the position in which the motor is stopped. Suitable counterweights, 47, of sufficient weight are employed to throw the stop, 46, to the right and keep it in such position that it will always engage the lug, 36. The stops, 46, are designed to remain in this position except when changed by the operator pressing down the shaft, 42. The shaft, 44, is held in alinement by brackets, 45, and 120 a link, 48, connects the end of the shaft, 44, with the lever, 49, which operates a four-way valve, 50, of any suitable and well known construction, said lever being slotted 125 to allow the shortening of the stroke of the 130

shaft, 44, and thereby compensating for the momentum of the carriage, and at the same time operating the four-way valve.

The operation of the foregoing parts is substantially as follows:

The motor propelled drums, 23, are set in motion by either electrical, air, or other motor power, thus causing the cable, 21, to move, which in turn moves cross bar, 10 to 10¹ without moving the head. As the cable continues to travel, the head which is connected to said cross bar by links, 16 and 17, is moved from A¹ to A¹⁻¹. While the head is moving from A¹ to A¹⁻¹, the lug, 36, has moved from 36 to 36¹ and during this movement of the lug, the shaft, 42, would have to be pressed down by the operator in order to allow the lug, 36, to pass through the first stop, 46. Otherwise, lug, 36 would engage stop, 46, at position shown by lug at 36² and would have pushed stop, 46, to position, 46¹ thus forcing lever, 49, to position, 49¹, and operating the four-way valve, 50, causing same to reverse the motor.

After the lug, 36 has passed through the first stop, 46, the operator releases shaft, 42, and the counterweights, 47, bring it back to its operating position, as shown by dotted lines in Fig. 7. In this position, the lug, 36, will encounter the second stop, 46, and push it to 46¹. The linear motion of shaft, 44, operates the four-way valve, 50, which reverses the motor, causing the lug, 36, and the cross bar, 10², to return to their original positions, 10¹. When the cross bar 10, reaches the position, 10¹, the lug, 36, encounters the first stop, 46, pushing it to 46² and again reversing the motor. In this manner the cross bar, 10, together with the head, A¹, and carriage would move backward and forward between certain limits which are determined by the distance apart of the stops, 46. This motion backward and forward of the carriage will continue until the operator wishes to close the press or stop the carriage at the limit of its travel from the press. In that case, the operator presses down the shaft, 42, thus bringing the large opening in the stop, 46, in line with the cable, 21, so as to allow the passage of the lug, 36, to its original position. The motion of the head and carriage can be controlled by the operator by operating wheel, 43, in the following manner: By bringing the hub, 40, on shaft, 42, in a neutral position, he can stop the motor; by turning wheel, 43, to the right he can close the press; or by turning it to the left he can open the press. When the lug, 36, is once admitted between stops, 46, it will continue automatically to cause the carriage to reciprocate by operating automatically the four-way valve, 50, by engaging stops, 46.

The foregoing is descriptive of one method of automatically operating and con-

trolling the travel of the carriage between certain limits. I do not, however, confine myself to the use of this specific mechanism as the salient features of my invention may be used in connection with other and different forms of controlling mechanism without departing from the spirit of the invention.

Having thus described my invention what I claim as new and desire to secure by Letters Patent is:—

1. In an apparatus of the character described, the combination with a tank or receptacle having an open end and a carrier movable to and from the tank and provided with a head adapted to close the open end of the tank or receptacle, and locking mechanism between the head and the tank or receptacle, of an automatic mechanism connected to and actuating the locking mechanism, said automatic mechanism adapted to move the head and carrier away from or toward the tank or receptacle in a plane parallel to the longitudinal axis of the tank.

2. In an apparatus, of the character described, the combination with a tank, or receptacle, a removable head forming a closure therefor, said head having a shaft projecting outwardly from its center, a collar slidable on said shaft, and locking levers carried by the collar and having outer ends engageable with the tank to lock the head to the tank, of a toggle mechanism for actuating said locking levers, said toggle mechanism including a movable cross-bar and connected links, means for tripping the toggle mechanism, and transmission means connected to the cross bar for moving the head to and from the tank or receptacle.

3. In apparatus of the character described, the combination with a tank or receptacle having an open end and a carrier operable to and from the tank or receptacle having a head at one end adapted to close the open end of the tank or receptacle, a shaft projecting centrally from the head, a sleeve slidably mounted on the shaft, and radially-disposed levers having inner ends pivoted to the sleeve and having outer ends adapted to engage fixed parts of the tank, an intermediate portion of said levers fulcruming against the head, of a second sleeve or collar concentric with said shaft and separated from the first-named sleeve, a double series of toggle-levers between the two sleeves, other toggle-levers carried by the double series of toggle levers and a movable cross-bar to which they are in turn connected, said cross bar being slidably supported and in its turn being connected to the movable tank head by means of toggle-joints which, when in a dead-center line, will permit the movement of the cross-bar to move the head without actuating the

- locking levers, and which when put out of dead-center position will permit the cross-bar to actuate the locking levers without moving the head.
5. In an apparatus of the character described, the combination with a tank or receptacle having an open end and a carrier operable to and from the tank or receptacle and having a head at one end adapted to 70 form a closure for the open end of the tank or receptacle, a shaft projecting centrally from the head, a sleeve slidably mounted on the shaft, and radially-disposed levers having inner ends pivoted to the sleeve and having outer ends adapted to engage a fixed part of the tank or receptacle, an intermediate portion of said levers fulcruming against the head, of a second sleeve or collar concentric with said shaft and separated from 75 the first-named sleeve, a double series of toggle-levers between the two sleeves, other toggle-levers carried by the double series of toggle-levers and a movable cross-bar to which they are in turn connected, said cross-bar being slidably supported and in its turn being connected to the movable tank or receptacle head by means of toggle-joints which when in a dead-center line will permit the movement of the cross-bar to move 80 the head without actuating the locking levers, and which when put out of dead-center position, will permit the cross-bar to actuate the locking levers without moving the head, a transmission means, and means for connecting said cross-bar to the transmission 85 means.
5. In apparatus of the character described, the combination with a tank or receptacle having an open end and a carrier adapted 90 for movement in and out of the same and provided with a head adapted to close the open end of the tank, of a locking mechanism between the head and the tank, means for releasing the locking mechanism, and means actuated by the releasing means for 95 moving the head relatively to the tank, and in a direction parallel to the longitudinal axis thereof.
8. In apparatus of the character described, the combination with a tank or receptacle 100 having an open end, and a carrier adapted for movement in and out of the same having a head adapted to close the open end of the tank, of a locking mechanism between the head and the tank, a toggle-mechanism 105 for unlocking said head, a linearly-operating mechanism for actuating the toggle-mechanism, and a second toggle-mechanism between the first toggle-mechanism and the linearly-operating mechanism and actuated 110 by the latter to impart linear movement to the head.
9. In apparatus of the character described having a tank or receptacle, a removable head forming a closure for one end thereof 115 and a locking mechanism for said head, a transmission means, connections between the transmission means and said locking mechanism for initially actuating the latter to release the head, and other connections between the transmission means and said head for imparting a linear movement to the unlocked head, said last-named connections including a cross-bar and toggle-levers connected thereto and to the head and 120 adapted when the joints thereof are in dead-center line to permit the cross-bar to move the head without actuating the locking mechanism.
10. In apparatus of the character de- 130
- locking levers, and which when put out of dead-center position will permit the cross-bar to actuate the locking levers without moving the head, a transmission means, and means for connecting said cross-bar to the transmission means.
6. In apparatus of the character described, the combination with a tank or receptacle having an open end and a carrier 75 adapted for movement in and out of the same, and provided with a head adapted to close the open end of the tank, of a locking mechanism between the head and the tank, a prime mover and connections controlled 80 thereby for releasing the locking mechanism, and means actuated by said prime mover for imparting movement to the head parallel to the longitudinal axis of the tank coördinately with the release of the locking mech- 85 anism.
7. In apparatus of the character described, the combination with a tank, or receptacle, having an open end and a carrier adapted for movement in and out of the same and 90 provided with a head adapted to close the open end of the tank, of a locking mechanism between the head and the tank, means for releasing the locking mechanism, and means actuated by the releasing means for 95 moving the head relatively to the tank, and in a direction parallel to the longitudinal axis thereof.
8. In apparatus of the character described, the combination with a tank or receptacle 100 having an open end, and a carrier adapted for movement in and out of the same having a head adapted to close the open end of the tank, of a locking mechanism between the head and the tank, a toggle-mechanism 105 for unlocking said head, a linearly-operating mechanism for actuating the toggle-mechanism, and a second toggle-mechanism between the first toggle-mechanism and the linearly-operating mechanism and actuated 110 by the latter to impart linear movement to the head.
9. In apparatus of the character described having a tank or receptacle, a removable head forming a closure for one end thereof 115 and a locking mechanism for said head, a transmission means, connections between the transmission means and said locking mechanism for initially actuating the latter to release the head, and other connections between the transmission means and said head for imparting a linear movement to the unlocked head, said last-named connections including a cross-bar and toggle-levers connected thereto and to the head and 120 adapted when the joints thereof are in dead-center line to permit the cross-bar to move the head without actuating the locking mechanism.
10. In apparatus of the character de- 130
- locking levers, and which when put out of dead-center position will permit the cross-bar to actuate the locking levers without moving the head, a transmission means, and means for connecting said cross-bar to the transmission means.
6. In apparatus of the character described, the combination with a tank or receptacle having an open end and a carrier 75 adapted for movement in and out of the same, and provided with a head adapted to close the open end of the tank, of a locking mechanism between the head and the tank, a prime mover and connections controlled 80 thereby for releasing the locking mechanism, and means actuated by said prime mover for imparting movement to the head parallel to the longitudinal axis of the tank coördinately with the release of the locking mech- 85 anism.
7. In apparatus of the character described, the combination with a tank, or receptacle, having an open end and a carrier adapted for movement in and out of the same and 90 provided with a head adapted to close the open end of the tank, of a locking mechanism between the head and the tank, means for releasing the locking mechanism, and means actuated by the releasing means for 95 moving the head relatively to the tank, and in a direction parallel to the longitudinal axis thereof.
8. In apparatus of the character described, the combination with a tank or receptacle 100 having an open end, and a carrier adapted for movement in and out of the same having a head adapted to close the open end of the tank, of a locking mechanism between the head and the tank, a toggle-mechanism 105 for unlocking said head, a linearly-operating mechanism for actuating the toggle-mechanism, and a second toggle-mechanism between the first toggle-mechanism and the linearly-operating mechanism and actuated 110 by the latter to impart linear movement to the head.
9. In apparatus of the character described having a tank or receptacle, a removable head forming a closure for one end thereof 115 and a locking mechanism for said head, a transmission means, connections between the transmission means and said locking mechanism for initially actuating the latter to release the head, and other connections between the transmission means and said head for imparting a linear movement to the unlocked head, said last-named connections including a cross-bar and toggle-levers connected thereto and to the head and 120 adapted when the joints thereof are in dead-center line to permit the cross-bar to move the head without actuating the locking mechanism.
10. In apparatus of the character de- 130

scribed, having a tank or receptacle, a removable head forming a closure for one end thereof and a locking mechanism for said head, a transmission means, connections between the transmission means and said locking mechanism for initially actuating the latter to release the head, and other connections between the transmission means and said head for imparting a linear movement to the unlocked head, said last-named means including a cross-bar and toggle-levers connected thereto and to the head and adapted when the joints thereof are out of dead-center position to permit the cross bar to actuate the head locking mechanism without moving the head.

11. In apparatus of the character described, the combination of a shell or casing

having a removable head, and means for moving the shell and head one relatively to the other for a substantial distance and in a plane parallel with the sides of the shell, said means including a cable at each side of and extending along the shell to a distant point in advance thereof, a transverse connection between the said cables, each of said cables being attached to the head, and head locking devices between the head and said transverse connection.

In testimony whereof I affix my signature in presence of two witnesses.

JASPER A. McCASKELL.
